UNITED STATES PATENT OFFICE.

EVAN JONES, OF PITTSBURG, PENNSYLVANIA.

GLASS-FURNACE.

SPECIFICATION forming part of Letters Patent No. 281,697, dated July 24, 1883.

Application filed April 21, 1883. (No model.)

To all whom it may concern:

Be it known that I, EVAN JONES, of Pittsburgh, in the county of Allegheny and State of Pennsylvania, have invented a new and useful Improvement in Glass-Furnaces; and I do hereby declare the following to be a full, clear, and exact description thereof.

My invention relates to an improvement in glass-furnaces; and it consists in the arrangement and construction of the fire-chamber, flues, and melting-pot, so as to utilize the smoke and gas which pass off from the fire-chamber, and thereby produce an intense heat where it will be most effectual in the melting and finishing process of the manufacture of glass.

I will now describe my invention, so that others skilled in the art may manufacture and use the same, reference being had to the accompanying drawings, forming a part of this specification, in which—

Figure 1 is a longitudinal vertical sectional view of my improved furnace. Fig. 2 is a horizontal sectional view through the line $x x$, Fig. 1. Fig. 3 is a vertical sectional view across the furnace through the line $y y$, Fig. 1; and Fig. 4 is a vertical cross-sectional view through the line $z z$, Fig. 1.

Like letters of reference indicate like parts wherever they occur.

In the drawings, a represents the fire-chamber, situated at one end of the furnace, and being provided with suitable grate-bars and doors.

Between the fire-chamber a and the outer wall and top of the furnace is an air-flue, $b b'$, formed by the vertical partition-wall c and horizontal wall d . Below the air-flue b' , parallel therewith, and extending from the top of the fire-chamber a over the bridge-wall e , is a gas or smoke flue, f . On the other side of the bridge-wall e from the fire-chamber a is the melting-pot g , resting on the walls $h h$. Between the melting-pot and the bridge-wall e , there is a space, i , for the passage of heat, excepting at the top, where a joint is formed, and the wall is built around the melting-pot. Over the melting-pot g is a close dome or roof, k , constructed of fire-brick tile, so as to form the space l and protect the contents of the melting-pot from the flames. Above the dome k is the

combustion-chamber m , being the space between the dome and the top wall of the furnace. Into this chamber m the gas or smoke flue f and air-flue b' enter at a point over the bridge-wall.

Extending from the top of the furnace down through the combustion-chamber m and dome k is a feed-cylinder, n , formed of fire-brick tile. In the rear of the melting-pot the combustion space or chamber extends down to the flues o , formed by the walls $h h$. These flues extend forward under the melting-pot into the smoke-chamber p . Leading from the smoke-chamber are the smoke-stacks q , in which are dampers r , by means of which the draft through the stack may be regulated.

At each side of the furnace, above the melting-pot, is an opening or gathering-hole, t , extending from the outer wall of the furnace into the space under the dome or roof k .

Along the rear end of the furnace, opening into the combustion-chamber m , are glory-holes s , for finishing purposes, and at the bottom of the chamber m , in the rear wall of the furnace, are a series of holes, u , to allow of the escape of any glass which may issue from a break or an overfill in the melting-pot.

The operation is as follows: The frit is fed into the melting-pot g through the cylinder n from the magazine n' , the cylinder is closed, and, the fire in the fire-chamber having been started, the flames and products of combustion pass through the flue f over the bridge-wall e into the combustion-chamber m , where they unite with the heated air, which is discharged through the air-flue b , it being heated by its passage therethrough. The flames pass over the dome k , down back of and at the sides of the melting-pot, into the flues o , under the pot, and thence into the smoke-chamber p and out by the smoke-stacks q . This combustion in the chamber m above, at the sides of, and below the melting-pot in the flues o produces an intense heat, which fuses the frit in a comparatively short time.

The advantages of my improved furnace are the saving of fuel, time, and labor.

Instead of the open melting-pot described, a closed melting-pot may be used; or the dome k may be omitted where the furnace is designed for the manufacture of common glass.

Having thus described my invention, what I claim, and desire to secure by Letters Patent, is—

1. In a glass-furnace, the combination of a gas-flue and air-flue opening into a combustion-chamber which extends above, back of, and below the melting-pot, substantially as and for the purpose specified.

2. In a glass-furnace, the combination of an air-flue and gas-flue opening into a combustion-chamber which extends over, back of, and underneath the melting-pot, and a dome or roof for protecting the interior of the melting-pot, substantially as and for the purpose specified.

15

3. In a glass-furnace, the combination of a glass-pot having a cover or dome-shaped roof, above which is the combustion-chamber, and a feed cylinder or chute leading from outside of the furnace into the glass-pot, substantially as and for the purpose specified.

In testimony whereof I have hereunto set my hand this 18th day of April, A. D. 1883.

EVAN JONES.
